(57) **CLAIM**

The ornamental design for a miniature personal computer, as shown and described.

DESCRIPTION

FIG. 1 is a top perspective view showing a preferred embodiment of a miniature personal computer showing our new design;

FIG. 2 is a bottom perspective view of a preferred embodiment of the miniature personal computer of FIG. 1;

FIG. 3 is a top plan view of a preferred embodiment of the miniature personal computer of FIG. 1;

FIG. 4 is a bottom plan view of a preferred embodiment of the miniature personal computer of FIG. 1;

FIG. 5 is a front side view of a preferred embodiment of the miniature personal computer of FIG. 1;

FIG. 6 is a rear view of a preferred embodiment of the miniature personal computer of FIG. 1;

FIG. 7 is a right side view of a preferred embodiment of the miniature personal computer of FIG. 1; and,

FIG. 8 is a left side view of a preferred embodiment of the miniature personal computer of FIG. 1; the broken lines shown illustrate portions of the computer and form no part of the claimed design.
